UNITED STATES PATENT OFFICE.

AURELIO SABIN FADDA AND JOHN DI LORENZO, OF PITTSBURG, PENNSYLVANIA.

AIR-SHIP.

No. 872,834.

Specification of Letters Patent.

Patented Dec. 3, 1907.

Application filed December 17, 1906. Serial No. 348,360.

To all whom it may concern:

Be it known that we, AURELIO SABIN FADDA and JOHN DI LORENZO, residents of Pittsburgh, in the county of Allegheny and 5 State of Pennsylvania, have invented a new and useful Improvement in Air-Ships; and we do hereby declare the following to be a full, clear, and exact description thereof.

This invention relates to air ships and more 10 especially those operating on the principle of an aeroplane.

The invention consists in combination and improvements hereinafter described and claimed.

15 In the accompanying drawings Figure 1 is a side view of our improved air ship; Fig. 2 is a plan view of the same; Fig. 3 is a cross section on the line 3—3 Fig. 1; Fig. 4 is a longitudinal section through the rudder; Fig. 20 5 is a vertical section through one of the air boxes; Fig. 6 is a similar section through one of the cushioning devices; and Fig. 7 is a cross section through one of the wings.

The body of the device is constructed as a 25 skeleton frame having a front vertical piece 1, a corresponding rear vertical piece 2, a pair of bottom pieces 3, a top connecting member 4, and suitable bracing and machinery supporting members. On the bottom members 3 of the skeleton frame I provide a suitable platform 5 which supports a motor 6 of suitable type, preferably one having maximum horse power per weight, such as of the Antoinette-Lavesseur type of alcohol motor. The main shaft of this motor has connected thereto cranks 7 to which are attached connecting rods 8 attached to a cross head or rod 9 which is connected to the ends of the piston rods 10 of the air compressors. 30 40 11. A pair of such compressors are used, one on each side. These air compressors are double, that is, a piston works into both ends thereof.

12 represents a pair of hollow buoyant 45 bodies which may be made of any suitable size necessary to lift the air ship in conjunction with the other mechanism hereinafter described for that purpose. These buoyant bodies are preferably of pear shape, as shown in Fig. 4, with the small ends projecting downwardly and having projecting into their lower ends pipes 13 coming from the compressors. These buoyant bodies are con-

nected by transverse members 14 and are secured to the skeleton frame in any suitable manner as by means of the lashings 15. In these bodies at their tops is a plate 17 which is yieldingly supported by means of springs 18. This plate acts as a cushioning means to receive the impact of the air coming from the compressors so as to prevent injury to the top of the thin shell of which these bodies are necessarily constructed. The compressors are to be run at a very high speed, and the highly compressed air is forced into the hollow 65 bodies 12 and assists in lifting the device.

At the forward end of the air ship I provide a pointed hollow body 20 which forms in effect a bow for the ship. This hollow front portion is constructed of a light frame 70 work 21 of wire mesh, say 5-inch mesh, covered with air tight silk, such as used for balloons, and which is protected on its outer surface by strips 22 of aluminium or other light material. This hollow body is designed 75 to be buoyant so as to assist in lifting the air ship, this buoyancy being accomplished by exhausting the air therefrom in order to create a partial vacuum. To prevent the body from collapsing when exhausted, it is braced 80 interiorly by means of cross bars 23 of bamboo, or other light and strong material.

At the stern of the ship we provide a rudder 25 which is a hollow body constructed similarly to the anterior portion 20 and is also 85 designed to have the air exhausted therefrom. This rudder is hinged on vertical pivots 26 and steering gear 27 of any suitable construction will be used. The air may be exhausted from the hollow rudder 25 and 90 hollow bow piece 20 by any suitable means, such as air pumps 28 driven in any suitable way from the motor 5. If desired we may use injectors located in tubes connected to the hollow bodies and having an air connection from the compressors, these injectors acting in the usual way to extract the air from the hollow bodies.

The ship is propelled by means of a propeller 34 at the forward end and a similar 100 propeller 35 at the rear end. These propellers are secured to a shaft 36 extending longitudinally of the ship and mounted in suitable bearings formed in supporting members 37 secured to the skeleton frame. This shaft 105 will be connected to the motor by any suit-

able transmitting gear or mechanism, such as the sprocket chain gearing 38. The ship is intended to be lifted primarily by the buoyancy of the bodies 12, bow portion 20 and rudder 25. To further assist in lifting the same we provide a pair of lifting propellers in the form of spiral bladed fans, or the like, 40 and 41. These are secured respectively on the shafts 42 and 43 which 10 are journaled in suitable bearings in the skeleton frame and are driven from the shaft 36 by means of suitable connecting gear, such as the bevel gears 44 shown. The shaft 42 is vertical while the shaft 43 is somewhat inclined as shown. We also provide mechanically driven wings to assist in lifting the ship. Two pairs of such wings 45 are shown. These wings are concave and are formed in sections hinged along the central line 46 of 15 said wings so that while being elevated the wings will collapse, but when being lowered they will open up and catch the air as will be readily understood. The wings are pivoted to suitable brackets or supports 47 and have 20 arms 48 projecting inwardly beyond said pivot points, to which arms are attached connecting rods 49 leading to cranks 50 on counter-shafts 51 driven from the motor 5 or from the shaft 36. The rotation of these 25 cranks will cause the wings to be oscillated on their pivots and as each wing is made up of hinged sections, it will collapse in its upward movement thus offering little resistance to the air, but on its downward movement, will expand and catch the air and assist in lifting the ship.

To the bottom of the skeleton frame is attached a rectangular frame 54 to which are journaled four wheels 55 for supporting the 30 ship on the ground. The rectangular frame 54 has a yielding or cushioning connection with the skeleton frame of the air ship, such as connecting to the corners thereof rods 56 which extend up through openings in the 35 skeleton frame. The cushioning effect is secured by means of hollow elastic bodies 57 interposed between the skeleton frame and the rectangular bottom frame, and being reinforced by the spiral springs 57 surrounding the rods 56 and located inside of these hollow elastic bodies. These cushioning devices prevent shock in alighting.

The operation of the air ship will be readily understood. All parts of the construction 40 are made with minimum weight for strength required. The motor will be a very powerful motor and of light weight so as to provide ample power for the propellers, lifting fans and wings, and also furnish ample air pressure for the buoyant bodies 12 and also power 45 to exhaust the bow piece 20 and hollow rudder 25. The ship is lifted by the combined effect of the buoyancy of the hollow bow, or

anterior piece 20, rudder 25 and buoyant bodies 12, and the lifting effect secured by 50 the rotation of the lifting fans 40 and 41 and of the wings 45. The ship is controlled and steered by means of the rudder and can be made to rise and fall as desired by simply speeding up or slowing down the motor. 55

What we claim is:

1. In an air ship, the combination with the body, of lifting and propelling means therefor, a hollow rudder hinged to said body, means for operating said rudder, and 60 means carried by the body and arranged to exhaust the air from said hollow rudder.

2. In an air ship, the combination of a skeleton body, and lifting and propelling means therefor, including a buoyant anterior 65 or bow portion immovably secured to the forward end of the body, a buoyant rudder or rear portion hinged to the rear end of the body, a motor on the body, and propellers driven from the motor and located respectively between the body and anterior portion and between the body and rudder.

3. In an air ship, the combination of a skeleton body, and lifting and propelling means therefor including a hollow buoyant 70 anterior or bow portion, and a hollow buoyant rudder or rear portion, said bow portion and rudder being of substantially the width and height of the body and containing the latter between them.

4. In an air ship, the combination with the body, of lifting and propelling means therefor, a hollow anterior portion immovably secured to the body, a hollow rudder hinged to the body, and means for exhausting 75 the air from said hollow anterior portion and rudder.

5. In an air ship, the combination of a skeleton body, lifting and propelling means therefor, a large hollow anterior or bow portion immovably secured to the forward end of the body, a hollow rudder hinged to the rear end of the body, said hollow anterior portion and rudder being of substantially the same height as the body, and means for rendering said hollow bodies buoyant.

6. In an air ship, the combination of a frame, buoyant bodies connected thereto, a motor mounted on the frame, vertical propelling fans and a pair of horizontal lifting fans operated from the motor, said lifting fans being one on a vertical axis and the other on an inclined axis, and collapsible and expandible wings also operated from the motor.

7. In an air ship, the combination with a body, of carrying and propelling means therefor, a wheeled frame below the body, and cushioning means between the same and the body, said cushioning means comprising 120 hollow closed elastic bodies.

8. In an air ship, the combination with
the body, of carrying and propelling means
therefor, a wheeled frame below the body,
spiral springs between the same and the
body, and closed hollow yielding or elastic
bodies inclosing said springs.

In testimony whereof, we the said AURE-

LIO SABIN FADDA and JOHN DI LORENZO
have hereunto set our hands.

AURELIO SABIN FADDA.
JOHN DI LORENZO.
